UNITED STATES PATENT OFFICE.

ERNEST ALBERT ALDINGA PAVY, OF NORTH PARADE, JAMESTOWN, SOUTH AUSTRALIA, AUSTRALIA.

ADJUSTABLE COMB FOR GRAIN-STRIPPING MACHINES.

955,098.

Specification of Letters Patent. Patented Apr. 12, 1910.

Application filed November 10, 1909. Serial No. 527,311.

To all whom it may concern:

Be it known that I, ERNEST ALBERT ALDINGA PAVY, mechanic, a subject of the King of Great Britain and Ireland, residing at 5 North Parade, Jamestown, State of South Australia, Commonwealth of Australia, have invented a certain new and useful Improved Adjustable Comb for Grain-Stripping Machines, of which the following is a 10 specification.

This invention relates to an adjustable comb for strippers and stripper harvesting machines in which the adjustment is made by increasing or decreasing the width of the 15 individual teeth.

The purpose of it is to enable the comb to be quickly adjusted to take a heavy or a light crop and also to enable a choke to be quickly and easily cleared.

20 In order that my invention may be clearly understood I will describe the same with reference to the accompanying drawings in which—

Figure 1 represents the piece of spring 25 steel bent and stamped out ready for bending into form. Figs. 2 and 3 represent the complete and shaped tooth. Fig. 2 shows it unattached, Fig. 3 shows it attached in 30 position. Fig. 4 shows a series of cross sections on the lines *a a b b* and *c c* respectively of Fig. 3. Fig. 5 represents upon a smaller scale portion of a comb showing the 35 slideable bar to which the teeth are pivoted and the means for operating same.

35 The invention relates particularly to the construction of the tooth and to its attachment to the comb bar and to a slideable operating bar.

The tooth A is formed from a strip of 40 spring steel. This strip is heated at about its center and bent into the form of a V, the material being thinned out outwardly to a fine edge to form the apex of the V as shown in Fig. 1. This flat piece of material 45 is then bent round at the center the two limbs of the V being brought into contact, the one partially overlapping the other, the thinned out apex or center portion of the strip forming a conical thimble or point to 50 the tooth with an overlap along the under-side. The outer edge of each limb is curved upward so as to give the tooth the usual fluting. Each tooth is formed from the one piece of spring steel, the adjustment of 55 the one limb over the other being obtained

through the spring thimble. The spring thimble is so set and tempered that when the tooth is unattached the two limbs stand somewhat apart at the heel end as shown in Fig. 2. The heel of the one limb is riveted or bolted to the comb bar B. The heel of the other limb is pivoted to a bar C, slideable in a space between the back of the comb bar and the front of the apron D, the upper face of such bar being on a 60 level with the upper face of the comb bar and the apron.

All the teeth A are attached to the one slideable bar C, which projects beyond the end of the cheek adjacent to the driver and 70 is provided with a handle E whereby the bar may be adjusted to the desired position. By moving the slideable bar the spaces between the teeth are adjusted according to the nature of the crop. If the crop is heavy 75 the bar is adjusted to increase the overlap of the two parts of each tooth thereby increasing the spaces between the adjacent teeth. If a lighter crop is met with the bar is adjusted to decrease the overlap of 80 the two parts of each tooth thereby decreasing the spaces between the adjacent teeth. Should a choke occur the spaces between the teeth are increased and the choke freed, after which the teeth are adjusted to their 85 normal width.

Having now fully described and ascertained my said invention and the manner in which it is to be performed I declare 90 that what I claim is—

1. An adjustable comb for grain stripping machines comprising, a series of spring steel teeth each having two partially overlapping limbs connected together at the forward end by a thimble integral therewith, a comb bar 95 to which one limb of each tooth is rigidly secured, a slideable bar to which the other limb of each tooth is pivotally secured situated between the comb bar and the apron and having its upper surface level with the upper 100 surface of same, and a handle whereby the slideable bar may be adjusted, substantially as described and for the purpose set forth.

2. An adjustable spring steel tooth having two limbs connected together at the forward 105 end by a thimble integral therewith, one of such limbs partially overlapping the other, substantially as described and for the purpose set forth.

3. An adjustable spring steel tooth having 110

two limbs connected together at the forward end by a thimble integral therewith, one of such limbs partially overlapping the other, the lower one being rigidly secured to the 5 comb bar and the upper one pivotally secured to a slideable bar provided with means whereby it may be operated substantially as described and for the purpose set forth.

In testimony that I claim the foregoing as my invention I have signed my name in 10 the presence of two subscribing witnesses this twenty-fourth day of September 1909.

ERNEST ALBERT ALDINGA PAVY.
